UNITED STATES PATENT OFFICE.

ROBERT H. PATTERSON, OF ATLANTA, GEORGIA.

DESIGN FOR A BOTTLE.

Application filed December 8, 1926. Serial No. 19,972. Term of patent 14 years.

To all whom it may concern:

Be it known that I, ROBERT H. PATTERSON, a citizen of the United States, residing in the city of Atlanta, in the county of Fulton, in the State of Georgia, have invented a new, original, and ornamental Design for Bottles, of which the following is a specification, reference being had to the accompanying drawing, forming part thereof.

The drawing is a front elevation of a bottle embodying my new design.

I claim:

The ornamental design for a bottle, as shown.

In witness of the foregoing, I affix my signature.

ROBERT H. PATTERSON.
